UNITED STATES PATENT OFFICE.

MARCUS AUERBACH, OF MONTREAL, QUEBEC, CANADA.

INDICATING-LOCK.

1,002,356.

Specification of Letters Patent.

Patented Sept. 5, 1911.

Application filed October 24, 1910. Serial No. 588,723.

To all whom it may concern:

Be it known that I, MARCUS AUERBACH, resident of 207 St. James street, in the city and district of Montreal, in the Province 5 of Quebec, in the Dominion of Canada, a subject of the King of Great Britain, have invented certain new and useful Improvements in Indicating-Locks, of which the following is a specification.

10 The invention relates to improvements in indicating locks, as described in the present specification and illustrated in the accompanying drawings that form part of the same.

15 The invention consists essentially in the novel construction and arrangement of parts, whereby at each and every time of opening, the lock mechanism is operatively connected with the recording mechanism and 20 the latter mechanism records by means of indicating hands through a peculiar multiple arrangement of toothed wheels.

The objects of the invention are to devise 25 a means of registering the number of times a door, case, or locked receptacle is opened, which cannot be tampered with, to provide a neat, durable and convenient form of device and generally to construct an indicating lock in a cheap and simple manner.

30 In the drawings, Figure 1 is a plan view of the invention as applied to a padlock, showing the indicating dials. Fig. 2 is a plan view of the interior mechanism in the same application of the invention. Fig. 3 is 35 a perspective detail of the key. Fig. 4 is an enlarged cross sectional view on the line A—B in Fig. 1. Fig. 5 is a plan view of the multiple arrangement of toothed wheels showing the upper wheels. Fig. 6 is a plan

40 view of the multiple arrangement of toothed wheels showing the lower wheels. Fig. 7 is an enlarged perspective detail of the grooved key post. Fig. 8 is a perspective detail of the rocking locking bar.

45 Like numerals of reference indicate corresponding parts in each figure.

Referring to the drawings, 1 is the back of the casing having the key plug hole 2 therethrough toward one side thereof.

50 3 is a key plug having a vertical slot 4 therein from end to end, said key plug being mounted on said back 1 in said hole 2.

55 5 is a vertical post having suitably spaced slots therein and rigidly secured to the back 1 adjacent to the key plug 3, said slots being

spaced to suit the wards of the particular key used.

6 is a rocker arm forming the locking bar having the bill hook end 7 extending partially around the cylindrical surface of the key plug 3, and the lug 8 at the other end from which projects upwardly the tooth 9.

10 is a post extending through a suitable pivot hole in the locking bar 6 intermediate of the length thereof and rigidly secured to the back 1 and having at the upper end thereof an internal thread, thus it will be seen that the locking bar 6 is pivoted on the post 10 and on the insertion of the key into the key plug 3 and on the turning of said 70 key, the bill hook end 7 of the locking bar 6 will be raised which will lower the lug end 8 of said locking bar correspondingly.

11 is the shackle of the lock, having the curved face 12 between the shoulders 13 75 and 14.

15 is a post extending through a corresponding pivot hole in the shackle 11 adjacent to the face 12 and rigidly secured in the back 1 immediately above the lug 8 so 80 that the teeth 9 engages the shoulder 14 in the closed position of the shackle 11. The upper end of the post 15 is internally threaded.

16 is a post rigidly secured to the back 1 85 and internally threaded at its upper end and situated immediately below the other end of the shackle 11 and above the bill hook end 7 of the locking bar 6.

17 is a flat spring having the looped end 90 18 around the post 16 and engaged by a suitable upwardly curved projection 19 from the locking bar. The other end of the spring 17 engages the shoulder 13 consequently the tension of said spring in the 95 locked position of the shackle is constant between the shoulder 13 and the projection 19, therefore, when the said locking bar 6 is turned on its pivot and the tooth 9 released from the shoulder 14, the tension of said 100 spring will cause the shackle 11 to turn rapidly on its pivot.

20 is a plate supported by the side shields 21 from the back 1 below the locking bar 6 and forming with said side shields a part 105 casing for the multiple arrangement of wheels and the recording mechanism.

22 is a spindle journaled in the back 1 and extending upwardly through the plate 20 and therebeyond. 23 is a toothed wheel 110

fixedly mounted on said spindle 22 adjacent to the back 1.

24 is a sleeve turning on the spindle 22 and journaled in the plate 20 and extending 5 upwardly therebeyond.

25 is a toothed wheel in ratchet form, and fixedly mounted on the sleeve 24 immediately under the plate 20.

26 is a finger fixedly secured at one end 10 to the sleeve 24 and extending laterally therefrom.

27 is a spindle journaled in the back 1 and in the plate 20 and extending above said plate.

28 is a toothed wheel fixedly mounted on the spindle 27 intermediate of the distance between the plate 20 and the back 1 and in alinement with the finger 26, said finger extending into engagement with said wheel 28.

29 is a finger at one end fixedly secured on the spindle 27 and extending laterally from said spindle into engagement with the wheel 28.

It will be understood from the arrangement of wheels just described, that the operation of the ratchet wheel 25 will insure the operation of all the wheels in rotation, that is to say, as the finger 26 is rigidly secured to the ratchet wheel sleeve shaft 24, at each 30 complete revolution of the said ratchet wheel 25, the said finger 26 will turn said toothed wheel 28 to the extent of one tooth. This happens at every complete revolution of the said wheel 25 and on the turning of the 35 said toothed wheel 28 a complete revolution, the finger 29 will engage the toothed wheel 23 and turn it to the extent of one tooth, it requiring the number of revolutions of the wheel 28 corresponding to the number of 40 teeth on the wheel 23 to turn the latter a complete revolution.

30 is a spring finger or pawl rigidly secured to the lug 8 at the lower end thereof and extending from said lug into engagement 45 with the ratchet toothed wheel 25, consequently at each rock of the locking bar 6 through the operation of the key in the key plug 3, the ratchet toothed wheel 25 will be turned to the extent of one tooth.

50 31 is a checking pawl of suitable spring material rigidly secured to the back 1 and extending therefrom into engagement with the ratchet toothed wheel 25, ahead of the finger pawl 30.

55 32 is a check pawl of suitable spring material secured to the back 1 and engaging the toothed wheel 23.

33 is a shield extending partially around the wheel 28 protecting the same, said wheel 60 28 rubbing said shield slightly to stiffen the operation.

34 is the cover completely closing in the mechanism described having holes 35 through which the posts 10, 15 and 16 project, the key hole 36 and the dial casings 37

and 38 surrounding the spindle holes 39 and 40 through which the spindles 22 and 27 project respectively and the sleeve 24 through the spindle hole 40.

41 is a dial spaced by a suitable number of markings corresponding to the number of teeth on the wheel 28, said markings being indicated on the turning of said wheel by the hand 42 which is secured on the top of the spindle 27.

75 44 is a dial having a double row of markings spacing the said dial off correspondingly to the ratchet toothed wheel 25 and the toothed wheel 23 respectively, said markings being indicated by the hand 45 secured to the sleeve 24 and the hand 46 secured to the spindle 22 respectively.

47 are screws inserted into the posts 10, 15 and 16 retaining said cover 34 securely to said back 1.

80 48 is a key to be inserted through the key hole 36 into the key plug 3, the wards of said key corresponding as regards distancing to the slots in the key post 5 and having a slight bend to engage the bill hook end 7 90 of the locking bar 6.

95 In the operation of this invention, the key is inserted as described and engages the bill hook end of the locking bar and this rocks the said locking bar on its pivot post which releases the tooth 9 from engagement with the shoulder 14, the shackle 11 is thus sprung outwardly as the tooth 9 slips from behind the shoulder 14. Coincidently with this movement of the shackle and the locking bar, the spring finger 30 engages the master or ratchet toothed wheel 25 and turns said ratchet tooth wheel to the extent of one tooth, this turns the hand 45 to the extent of one space on its corresponding dial and marks the lock as having been opened once. This operation is continued until the hand has traveled completely around the dial when it will be found on the last stroke that the hand 42 has turned to the extent of one 100 space on its corresponding dial through the action of the finger 26 in engagement with the wheel 28. After the hand 42 has covered the dial 41 then the hand 46 is operated through the finger 29 in engagement with 110 the wheel 23.

115 The multiplicity by this arrangement of recording mechanism will be readily understood as in the first place, the ratchet wheel must turn to the full extent of the number of its teeth before the second wheel is operated to the extent of one tooth, therefore, the first wheel must perform the number of revolutions corresponding to the number of teeth on the second wheel, and similarly in 120 regard to the third wheel, the second wheel must be turned a complete revolution for each tooth of the third wheel, so it will readily be seen how it multiplies, for in 125 wheels of 24, 12 and 18 teeth respectively, 130

taking them as the first, second and third wheels according to their operation, the number of times that the lock opens that may be recorded is over five thousand, therefore, the increase in the number of teeth will naturally increase that total tremendously.

This mechanism has been described herein as applied to a padlock, which is the most convenient form of device for the use of 10 this invention, but it will readily be understood that various applications of the invention may be made, such as applying it to door locks, desk locks and other things, though the general form and arrangement 15 of the mechanism will remain substantially the same, however, a certain latitude of construction will likely be desirable, so long as the salient features pointed out in the 20 claims for novelty following are adhered to.

What I claim as my invention is:

1. In an indicating lock, a lock mechanism, a multiple arrangement of toothed wheels having a master wheel operatively connected to said lock mechanism, a finger 25 rotating with said master wheel and operating a second wheel at each complete revolution of said master wheel, the second wheel rotating apart from said master wheel, a finger rotating with said second wheel and 30 operating a third wheel in vertical arrangement with said master wheel, a dial for said master wheel and third wheel, a dial for said second wheel, and indicating hands operated by said wheels.

2. In an indicating lock, a lock mechanism, a multiple arrangement of toothed wheels having a master wheel operatively connected to said lock mechanism, a sleeve shaft carrying said master wheel, a finger 35 rotating said sleeve shaft and master wheel, a second wheel engaged by said finger, a spindle carrying said second wheel, a finger rotating with said second wheel and spindle, a spindle extending through the aforesaid 40 sleeve shaft, a third wheel mounted on said spindle and engaged by the aforesaid second finger, an indicating hand mounted at the upper end of said sleeve shaft, an indicating hand mounted at the upper end of 45 said spindle extending through the sleeve shaft, and an indicating hand mounted at the upper end of the other spindle.

3. In an indicating lock, a lock mechanism, a multiple arrangement of toothed 50 wheels having a master wheel operatively connected to the lock mechanism, a back plate, a front plate, a pair of spindles journaled in said plates and extending therebetween, a sleeve turning on one of said 55 spindles and journaled in the front plate and having said master wheel mounted thereon, a finger fixedly mounted on said sleeve and extending laterally therefrom, a wheel mounted on the other spindle and engaged 60 by said finger, a finger fixedly mounted on 65

said other spindle and extending laterally therefrom, a third wheel fixedly mounted on the spindle extending through the sleeve toward the lower end thereof and operated by the finger extending from the other 70 spindle, an indicating hand mounted on said other spindle, an indicating hand mounted on said sleeve, and an indicating hand mounted on the spindle extending through said sleeve. 75

4. In an indicating lock, a lock mechanism, a back plate, a front plate, a pair of spindles extending between said front and back plates and journaled, a sleeve turning on one of said spindles, a ratchet toothed 80 wheel fixedly mounted on said sleeve, a finger fixedly mounted on said sleeve and extending laterally therefrom, a second toothed wheel fixedly mounted on the other spindle and engaged by said finger at 85 each complete revolution of said ratchet toothed wheel, a finger fixedly mounted on the spindle of said second toothed wheel and extending laterally therefrom, a toothed wheel fixedly mounted on the first spindle 90 and engaged by the second finger, a pawl secured to said lock mechanism and engaging said ratchet wheel, a dial mounted on said front plate through which said spindles extend, and indicating hands secured 95 to the top end of said spindles and said sleeve respectively.

5. In a device of the class described, in combination, a lock mechanism, a back plate, a partial supplementary casing secured on top of said back plate and formed of a minor front plate and side shields extending partially therearound between said back plate and said minor front plate, a pair 100 of spindles extending from said back plate through said minor front plate, a sleeve mounted on one of said spindles and journaled in said minor front plate, a ratchet toothed wheel fixedly mounted on said sleeve, a pawl from said lock mechanism engaging said ratchet wheel, a check pawl extending from said back plate and engaging said ratchet wheel, a second wheel mounted on the second spindle, a finger operated by 105 said ratchet wheel and engaging said second wheel at each complete revolution of said ratchet wheel, a third wheel mounted on the first spindle, a finger operated by said second wheel and engaging said third wheel, a check pawl secured to said back plate and 110 engaging said third wheel, and indicating hands mounted at the upper end of said spindles and sleeve respectively. 115

6. In a device of the class described, in combination, a lock mechanism, a dial having a row of numerical markings therearound a dial having a double row of numerical markings therearound, a case supporting said dials and lock mechanism, a spindle extending from said case to said 125 130

double dial; a sleeve turning on said spindle and extending to said double dial, a spindle extending from said case to said single dial, indicating hands mounted on said spindles and said sleeve respectively, a master wheel in said case operatively connected with said lock mechanism, a second wheel on said single dial spindle operated by the rotation of said master wheel at predetermined intervals, and a third wheel mounted on the first spindle and operated at predetermined intervals by the rotation of said second wheel.

7. In a device of the class described, in combination, a recording mechanism, a rocker arm forming the locking bar operatively connected with said recording mechanism, a spring member compressed between said rocker arm and the bolt member, and a shackle member released by said locking bar and sprung therefrom by said spring member.

8. In a device of the class described, in

combination, a recording mechanism having a master ratchet toothed wheel, a rocking locking bar having a lug at one end and a tooth projecting upwardly from said lug, a shackle having two shoulders in the pivoted end thereof, one of said shoulders being engaged by said toothed projection from the locking bar, a spring at one end engaging the other shoulder in said shackle and at the other end engaging said locking bar, a post pivotally supporting said spring, a back plate supporting said posts and locking bar, and a spring pawl extending from the lug of said locking bar into engagement with said ratchet wheel.

Signed at the city of Montreal, Quebec, Canada, this 22nd. day of October, 1910.

MARCUS AUERBACH.
